RICHARD GRIESER, OF NEW YORK, N. Y., ASSIGNOR TO POLLARD-ALLING MANUFACTURING COMPANY, OF NEW YORK, N. Y., A CORPORATION OF NEW YORK.

PRINTING-PLATE CHAIN.

No. 866,928

Specification of Letters Patent.

Patented Sept. 24, 1907.

Application filed September 8, 1906, Serial No. 277,618. Renewed July 13, 1907. Serial No. 884,481.

To all whom it may concern:

Be it known that I, RICHARD GRIESER, a citizen of the United States, residing in New York, in the county of New York, borough of Manhattan, and State of New York, have invented certain new and useful Improvements in Printing-Plate Chains, of which the following is a specification.

This invention is for producing an improved printing plate and printing plate chain for use in addressing machines, and the plates of which may be readily assembled one with another without bending either of them, and when assembled and turned slightly on the connecting pintles they will be locked from disassembly, and the pintles of which plates are formed for reducing friction and reinforced for increasing the stability of the chain.

For addressing machines and similar purposes each address is formed on a plate generally by striking up type faces from the face of the thin sheet metal plate 20 and such plates are articulated together into a chain, which will be rolled up and as used will be unrolled and rolled up as it is unrolled. When addresses are to be changed, eliminated from the list, or new ones added, the chain will be separated at the appropriate place 25 and plates added or removed as required and the plates of the chain again pivoted together. One thing to be desired in such plates is that they may be assembled and disassembled when in the proper positions easily and without bending either the plates or their hinge 30 portions; and also that upon being turned slightly from the position of assemblage the plates will be securely locked together and their pivotal action will be free and unencumbered, and when the plates are subjected to strain the hinge connections will be strong enough 35 to resist the strain, particularly so when the plates are turned far back past their normal position and to a position where their stop faces tend to prevent further turning.

The pintles of the chains as now frequently constructed will when the plates are turned with their faces toward each other bend, and upon continued strain spring out of their sockets, thus disconnecting one portion of the chain from the remainder. But the present improvement so disposes the metal of the pintle portions 45 that it not only is stiffened but reinforces the neck carrying it, and the neck is so disposed relative to the plate that it and the plate mutually reinforce each other, the connection between the pintle and plate being stiffened and the hinge carrying portion of the plate being 50 strengthened.

In the drawings accompanying and forming a part of this specification, Figure 1 is a view of a portion of the chain looking at the printing faces of the plates, which plates embody the present improvement. Fig. 2 is an 55 enlarged perspective view showing portions of two

plates and illustrating the hinge members. Fig. 3 is an end view of a pair of such plates, enlarged to about double the size found convenient for use, in the position they will occupy when being assembled one with another and before they have been turned into a locking position. Fig. 4 is an enlarged and broken off end view of the hinge members of a pair of plates in about the same relative positions as shown in Fig. 3. Figs. 5 and 6 are similar views respectively showing the plates turned into a locking position. Figs. 7 and 8 show a 60 position with the back faces of the plates turned at about right angles to each other. Figs. 9 and 10 show the articulated plates in about the same plane; and Figs. 11 and 12 show the plates turned with their printing faces at an angle one to the other, and in which 70 position the plates are represented as having reached the limit of their relative angular movement.

In one of the views a number of plates 20 are illustrated articulated together for use, each plate having a flange portion 21 along one edge curved toward the 75 back face 22 and away from the printing face 23, upon which latter face suitable type will be formed. The edge 29 of the flange reaches toward the back face 22. Near each end of the plate the flange 21 is cut away as at 24 for receiving the neck 25 carried by the edge of a 80 similarly formed plate and the necks carry pintles 26 for entrance into the space 27 of the curved flange. These parts constitute the hinge members for the plates.

It will be seen that the neck 25 is sharply offset from 85 the plate as at 28, that is, the neck is in a plane at an angle to the plane of the plate. This reinforces the neck and also stiffens the plate at the locality of the neck. The pintles and the end of the neck are longitudinally channelled or curved on a line parallel with 90 the edge of the plate, which will stiffen the pintles and the neck and further strengthen the region of the plate carrying the neck.

By reference to Fig. 2 it will be seen that the face 45 of the pintles is a segment of a cylinder, as is also the 95 interior face 55 of the curved flange. This gives a strong connection and one offering but little frictional resistance in use. When two plates are brought together for assemblage, see Figs. 3 and 4, designated for convenience 40 and 50 respectively, the pintles 100 26 of the plate 40 will be slid, not sprung, under the curled flange 21 of the plate 50. It will be seen that the edge 41 of the flange 42 as it were of the pintles clears the edge 51 of the flange 21, and that the edge 43 will by a continuation of the movement be caused 105 to pass under the edge 51, when the plates will be assembled with the faces 45 and 55 in working engagement, and a relative angular movement of the plates will cause the face 45 to turn on the face 55, which will take the edge 43 past the edge 51 and place the hinge 110

members in a position from which they cannot be disassembled except by returning to the initial position, and so far as disassembly is concerned the plates may be regarded as in a locked position. In the positions 5 shown in Figs. 7 and 8 the back faces of the plates are at about right angles to each other, and there is a considerable area of bearing face presented of the portion 46 on 56 and 47 on 57, giving a good bearing and one which will prevent shucking of the plates; in fact even 10 in the position of Figs. 5 and 6 this bearing at each side of the pintle portion is illustrated. In Figs. 9 and 10 relatively large bearings are had between the portions 48 and 58. In this position the plates are as they will be when the chain of plates is nearly straight. Figs. 15 11 and 12 show the plates bent backwardly from the assembling position and until the face 49 has abutted the face 59, and such engagement with the bearing between the portions 48 and 58 prevents the further relative movement of the plates. In each of Figs. 4, 20 6, 8, 10 and 12 only such reference characters have been applied as are mentioned in the description of such figures. This will avoid an unnecessary confusion of reference characters.

Having thus described my invention, I claim as new:

- 25 1. A chain for addressing machines embodying a number of plates articulated together and each plate comprising a type-receiving portion and a curved flange along one edge, it having a number of notches, the other edge having a number of necks bent sharply at an angle to the plane of the plate, and tongues projecting from the necks in a direction longitudinally of the plate and in a different plane from the plane of the necks.
- 30 2. A printing plate chain comprising a number of sheet metal plates articulated together and each plate having a flange portion curled over from its printing face along one
- 35

edge, said flange having an interruption near each end of the plate, and said plate also having a pair of offset substantially flat necks for entering said interruptions of an adjacent plate, and longitudinally curved pintles carried by the necks for entrance within the curled flange of said adjacent plate. 40

3. A printing plate chain comprising a number of plates articulated together and each plate having a flange portion curled over from its printing face along one edge, said flange having an interruption near each end of the plate, and said plate also having a pair of offset necks for entering said interruptions of an adjacent plate, pintles carried by the neck, and a flange carried by and reinforcing the end of the neck and the edges of the pintles for entrance within the curled flange of said adjacent plate. 45

4. A printing plate embodying a type or printing portion of plate like formation having along one edge a curled flange having its edge nearly reaching the back face of the plate and transversely notched near each end, and at the other edge having offset necks for entering the notches on a similarly formed plate, and said necks having pintles stiffened by longitudinal channels for entrance between the flange edge and back face of said similarly formed plate. 50

5. A printing plate embodying a sheet metal body portion having pintle sockets at one edge, and at the other edge transversely disposed necks and longitudinally disposed pintles carried by the necks and formed of said sheet metal and curved about their longitudinal axis, disposing the metal of the pintle transversely of the metal of the necks. 55

6. A printing plate embodying a sheet metal body portion having pintle sockets at one edge, and at the other edge necks offset at an angle from said body, and pintles carried by the necks and curved about their longitudinal axis transversely of the necks. 60
